UNITED STATES PATENT OFFICE

JOHN SOMMA, OF NEW YORK, N. Y.

EXTENSION TABLE

Application filed June 21, 1932. Serial No. 618,433.

This invention relates to extension tables. The main object of the invention is to provide an improved extension table the top of which may be extended in either one or two directions as desired. Some features of the invention may, however, be embodied in a table which is extensible in only one direction.

Tables constructed so that they may be extended in one direction are well known, a familiar example of such tables being the usual dining table constructed so that the two ends may be drawn apart to leave a space between the two parts of the table top for the insertion of extra leaves.

A table embodying all the features of the present invention has a main table top and end and side extension top sections or leaves, and a supporting frame or body which is most desirably rectangular and of nearly the same length and breadth as the table top, the connecting means between the main table top and the supporting body being such that the main table top may rest in normal position in which it alone serves to form the top of the table, or may be connected to the supporting body in a position offset from its normal position in one direction to permit one of the extension leaves to be positioned on the support to extend the top in the opposite direction, or may be connected to the supporting body in a position offset diagonally from its normal position to permit both of the extension leaves to be positioned on the support to provide a table top which is extended in two transverse directions, that is, both lengthwise and crosswise of the table.

An approved embodiment of the invention is shown by way of example in the accompanying drawings, in which:

Fig. 1 is a perspective view of the table, showing the main part of the table top in diagonally offset position preparatory to placing the end and side extension top sections in position;

Fig. 2 is a plan view of the supporting body or frame;

Fig. 3 is a section on the line 3—3 of Fig. 2, with the main top section in position;

Fig. 4 is a section on the line 4—4 of Fig. 3;

Fig. 5 is a top plan view of the table with only the main section of the table top in position;

Fig. 6 is a top plan view of the table with the end extension top section in position;

Fig. 7 is a top plan view of the table with both end and side extension top sections in position;

Fig. 8 is a section on the line 8—8 of Fig. 7;

Fig. 9 is a section on the line 9—9 of Fig. 7; and

Fig. 10 is a vertical section through one of the headed projections on the table top sections and its cooperating slot.

The table comprises a table top supporting frame or body generally designated as 10, supported by a pair of pedestal type legs 11. The table top comprises a main top section 15, an end extension top section or leaf 16 and a side extension top section or leaf 17.

The supporting body comprises an upper frame 21 which serves as the immediate support for the main top section and also for the extension leaves when in use. Below this frame 21 (see Figs. 3 and 4) the body is formed to provide a shallow storage compartment 22, having a hinged door 23 at one end to receive the end section or leaf 16 when not in use, and a shallow compartment 24 beneath the compartment 22 and having a hinged end door 25 to hold the side section 17.

For securing the main table top 15 to the supporting frame 21 and for permitting it to be shifted from its normal position in which it serves as the complete top of the table as indicated at Fig. 5 to an endwise offset position as indicated at Fig. 6, or to a diagonally offset position as indicated by Fig. 7, the frame 21 is in the construction shown formed with an undercut slot 30 extending longitudinally of the frame and having two spaced parallel undercut slots 31 and 32 extending transversely therefrom, and the table top 15 is provided with two shouldered or headed studs 33, of which one is shown in Fig. 10, extending from the under side thereof and

65

70

85

90

95

100

spaced apart longitudinally of the top a distance corresponding to the distance between the transverse slots 31 and 32. The undercut slots 30, 31 and 32 are provided by means 5 of a slotted metal plate 34 having two laterally extending slotted arms 35 and 36, this plate and its arms being set into the upper surface of parts of the frame 21 over channels cut in the frame parts as shown in Fig. 10. The slot 31 extends from one end of the longitudinal slot 30 near one end of the table, and the slot 32 extends from the slot 30 at a point near the middle of the length of the frame 21, and from this point the slot 30 15 extends on for a suitable distance toward the other end of the frame 21, ending at such a point as not to interfere with the placing of the end extension leaf 16. The holding studs 33 on the under side of the table top 15 are positioned so that when one of the studs is 20 in the right hand end of the slot 30, as viewed in Fig. 2, the top 15 will be in its normal position shown by Fig. 5, and when the top is moved lengthwise to bring the other stud to the other end of the slot 30, the top 15 will be 25 in the longitudinally offset position shown by Fig. 6. When in this position the two studs will be opposite the ends of the two transverse slots 31 and 32, so that the top 15 30 may then be moved transversely to the diagonally offset position shown by Fig. 7, in which position the studs 33 will be at the outer ends of the slots 31 and 32 and the top 15 will then have been shifted diagonally from 35 its normal position. In order to permit the holding studs 33 to be entered into the slot 30, the slot is formed with two suitably spaced enlargements 37.

Instead of relying entirely on the engagement of the holding studs with the ends of the slot 30 to limit the longitudinal movement of the table top 15, a stop cleat 38 is desirably secured to the under side of the table top in 40 position to engage the end cross piece 39 of the frame 21 when the table top is in its normal position and to engage a cross piece 40 of the frame 21 when the table top has been moved to the position shown by Fig. 6. A recess 41 is formed in the frame to receive the stop cleat 38 when the table top 15 is moved 45 transversely to the position shown by Fig. 7.

When it is desired to lengthen the table without increasing its width, the main top 15 is moved longitudinally to the offset position 50 shown in Fig. 6 in which it extends beyond one end of the supporting frame 21 and a portion of the supporting frame at the other end is left uncovered. The end leaf 16 is then placed on the uncovered end portion 55 of the supporting frame with its inner edge abutting against the end edge of the main top 15. The width of the leaf 16, or its dimension widthwise of the table when positioned on the supporting frame, is equal 60 to the width of the main top 15, and its

length longitudinally of the table is such that when positioned on the uncovered end portion of the supporting frame abutting against the end of the main top 15 it will project beyond the end of the supporting 70 frame a distance equal to the distance which the other end of the main top 15 projects beyond the supporting frame when in its longitudinally offset position. In order that the leaf may when not in use be stored in the 75 compartment 22, it is made in two parts hinged together on the line 45 of Figs. 6 and 7 and as shown at 46 in Fig. 4 so that the two parts may be folded together. For securing the leaf 16 on the supporting frame, the edge 80 of the leaf which abuts against the end edge of the main top 15 is formed to interlock with such edge of the main top and the under side of the leaf is provided with a pair of shouldered or headed studs similar to the studs 85 33 of the main top adapted to be entered into holding engagement in a corresponding pair of undercut slots 47 suitably positioned in a part of the supporting frame. These slots like the slots 30, 31 and 32 are provided by 90 means of slotted metal plates set into the upper surface of a part of the supporting frame over cut away portions thereof, each slot being of right angled form, one arm extending longitudinally of the frame and having an enlarged portion at its outer end for entrance of the shouldered stud and the other arm extending from the inner end of the slot transversely thereof.

The edges of the main top 15 are formed 100 as shown in the drawings with a projecting bead *a*, and the inner or abutting edge of the end leaf 16 is complementarily grooved, as best shown at *b* in Fig. 9. In placing the leaf 16 on the uncovered end portion of the 105 supporting frame its holding studs are first entered through the enlarged ends of the slots 47 and the leaf is then slid inward to bring its inner edge into interlocking engagement with the end edge of the table top 15 110 and is then slid sidewise to move its holding studs into the transverse portions of the slots 47. The leaf will then be held releasably in the position shown in Fig. 6, forming 115 with the main top 15 a longitudinally extended top for the table.

When it is desired to widen the table top as well as to lengthen it, the main top 15 is moved into the position shown by Fig. 7, thus leaving one side portion as well as one 120 end portion of the supporting frame uncovered. The end leaf 16 is then positioned as before but with its holding studs entered into a second pair of undercut slots 48 provided in a part of the supporting frame and spaced laterally from the slots 47 a distance equal to the transverse movement of the main top 15. The side leaf 17 is then positioned on the 125 uncovered side portion of the supporting frame with its inner edge abutting against 130

the side edge of the main top 15 and the aligned side edge of the end leaf 16. This side leaf 17 is also formed in two parts 17a and 17b so that it may be stored in its compartment 24. Instead of having the two parts of the side leaf hinged together, they are, as shown, provided one with dowel pins 50 and the other with holes to receive the projecting ends of the pins when the parts 10 are placed end to end (see Fig. 8). The edge of the side leaf 17 which abuts against the side edges of the main top 15 and leaf 16 is grooved to interlock with the edges of the main top and end leaf, and the leaf 17 is 15 secured in position on the supporting frame by holding studs similar to the studs 33 of the main top on the under side of the leaf entering right-angled undercut slots provided in parts of the supporting frame. 20 There are in the construction shown three pairs of these slots 51, 52 and 53 respectively. The slots are formed in metal plates set in the upper surface of the frame parts and each has an enlarged outer end to permit entrance of the corresponding holding stud, each slot extending first inwardly crosswise of the table and having a transverse inner end portion. One of the parts, 17a, of the side leaf has a pair of holding studs near 25 each end, and the other part, 17b, has one pair of holding studs near its outer end, and the slots 51, 52 and 53 are positioned correspondingly so that when the holding studs 30 have been entered into the enlarged outer ends of the slots and the leaf pushed inward to bring its inner edge against the edges of the main top 15 and the end leaf 16 and then moved longitudinally to the left as the table is viewed in Figs. 1, 2 and 7, the leaf will 35 40 be positioned with its end edges in line with the outer ends of the main top 15 and end leaf 16 and with its inner side edge in interlocking engagement with the abutting edges of the main top and end leaf. 45 The main top 15 has both side edges and both end edges finished with a projecting beading *a*. The end leaf 16 has the same beading *a* on its two side edges and on one end edge with the other end edge complementarily grooved; and the two parts of the 50 side leaf have the same projecting beading on one side edge and on one end edge and have the other side edge complementarily grooved. The top of the table will 55 thus have the same edge finish all around whether it is formed by the main top 15 alone or by the main top and the end leaf or by the main top and both the end and the side leaves, and the abutting edges of the main top and the end leaf, and of the main top 60 and end leaf and the side leaf, will have complementarily formed interlocking edges which aid in holding the end and side leaves 65 in position on the supporting frame and in

providing a rigid table top of either of the three possible sizes.

To permit the two parts of the end leaf 16 to fold flat together as shown in Fig. 4, the part which is not provided with the holding studs has suitable recesses therein (not shown) to receive the holding studs on the other part. Similarly, to permit the two parts 17a and 17b of the side leaf 17 to lie flatwise together with their under surfaces in contact as shown in Figs. 3 and 4, the under sides of each part are recessed to receive the holding studs of the other part. Any suitable means may be provided for holding the hinged doors 23 and 25 at the ends of the storage compartments 22 and 24 closed and for permitting them to be opened when desired.

What is claimed is:

1. A table, comprising in combination a supporting body, a rectangular main table top, means for holding said main top to the supporting body in three positions, that is, normal position to serve as the complete top of the table, an offset position to uncover a part of the supporting body beyond one edge of the main top, and an offset position to uncover parts of the supporting body beyond two adjacent edges of the main top, extension leaves adapted to rest on uncovered parts of the supporting body, and means for detachably securing said leaves in position on the supporting body.

2. A table, comprising in combination a supporting body, a rectangular main table top of substantially the same length and width as the supporting body, means for holding said main top to the supporting body in three positions, that is normal position to serve as the complete top of the table, an offset position to uncover a part of the supporting body beyond one edge of the main top, and an offset position to uncover said part of the supporting body and another part of the supporting body beyond an adjacent edge of the main top, an extension leaf adapted to rest on the first said uncovered part of the supporting body and having an edge formed to interlock with the first said edge of the main top, an extension leaf adapted to rest on the other uncovered part of the supporting body and having an edge formed to interlock with said adjacent edge of the main top and with the abutting edge of the first said extension leaf, and means for detachably securing said leaves in position on the supporting body.

3. A table, comprising in combination a supporting body, a rectangular main table top of substantially the same length as the supporting body, means for holding said main top to the supporting body in normal position to serve as the complete top of the table and in an offset position to uncover a part of the supporting body beyond one

- edge of the main top, an extending leaf adapted to rest on such uncovered part of the supporting body and having an edge formed to interlock with said edge of the main top, and means for detachably holding said leaf to the supporting body.
4. A table, comprising in combination a supporting body, a rectangular main table top, means for holding said main top to the supporting body in a normal position to serve as the complete top of the table and in a position offset diagonally from its normal position to uncover portions of the supporting body, extension leaves adapted to rest on the uncovered portions of the supporting body when the main top is in said diagonally offset position, and means for detachably securing said leaves in position on the supporting body.
5. A table, comprising in combination a supporting body, a rectangular main table top of substantially the same length and width as the supporting body, means for slidably connecting said main top to the supporting body to permit the main top to slide relatively to the supporting body first longitudinally of the body and then transversely thereof, an end leaf of the same width as the main top adapted to rest on an uncovered end portion of the supporting body with one edge abutting the end of the main top, and a side leaf of a length equal to the combined length of the main top and the end leaf adapted to rest on an uncovered side portion of the supporting body in abutting relation to side edges of the main top and the end leaf, and means for detachably securing the end leaf and the side leaf in said positions.
6. A table, comprising in combination a supporting body, a main table top of substantially the same length as the supporting body, an undercut slot in the face of one of said elements, holding means extending from the face of the other of said elements into said slot and formed to coat with the slot to hold the main top to the supporting body while permitting the top to slide on the body to uncover a portion of the body, an end leaf adapted to rest on the uncovered portion of the body and against the edge of the main top, and means for securing said end leaf in such position.
7. A table comprising in combination a supporting body, a main table top of substantially the same length as the supporting body, means for slidably connecting the main top to the supporting body to permit the top to slide relatively to the body to uncover a portion of the body, an extension leaf adapted to rest on the uncovered portion of the body and against the edge of the main top, the supporting body and the extension leaf being provided with means for securing the leaf to the body, said means comprising a right angled undercut slot in the face of one of
- said parts and a shouldered stud extending from the face of the other of said parts, one arm of said slot being substantially perpendicularly to the edge of the main top against which the extension leaf abuts and having at the end farthest from said edge an enlarged portion to receive said lug, the other arm of the slot being substantially parallel to said edge.
8. A table, comprising in combination a supporting body, a rectangular main table top of substantially the same length and width as the supporting body, means for securing the main top to the supporting body and for permitting it to be moved on the body first longitudinally from its normal position to uncover an end portion of the body and then transversely to uncover a side portion of the body, said means comprising a main undercut slot in the face of one of said elements and two branch undercut slots extending one from one end of the main slot and the other from an intermediate point in the main slot, and two spaced shouldered studs extending from the face of the other of said elements into said slot, and extension leaves adapted to be secured on the uncovered portions of the supporting body in abutting relation to the main top.
- In testimony whereof, I have hereunto set my hand.
